United States Patent Office

Des. 233,685
Patented Nov. 19, 1974

233,685

CURTAIN FABRIC

Peter E. Schroeder, Arni, Switzerland, assignor to Gardisette International AG, Zurich, Kirchenweg, Switzerland

Filed Mar. 26, 1973, Ser. No. 344,536

Claims priority, application Germany Oct. 7, 1972

Term of patent 14 years

Int. Cl. D5—02

U.S. Cl. D47—6 E

The single figure is a plan view of a curtain fabric showing my new design, the fabric is shown over a dark background for purposes of illustration only.

I claim:

The ornamental design for a curtain fabric, substantially as shown and described.
